UNITED STATES PATENT OFFICE.

EDWIN W. GOESER, OF LOS ANGELES, CALIFORNIA, ASSIGNOR, BY MESNE ASSIGNMENTS, TO EMSCO DERRICK & EQUIPMENT COMPANY, OF LOS ANGELES, CALIFORNIA, A CORPORATION OF CALIFORNIA.

WIRE-LINE-GUIDE ATTACHMENT FOR OIL-WELL DERRICKS.

Application filed March 29, 1924. Serial No. 702,893.

My invention relates to the equipment used in oil well drilling and production, and more particularly to the hoisting equipment ordinarily installed in an oil well derrick.

5 This equipment consists of suitable sheaves installed at the top of the derrick, and collectively called, with their associated parts, a crown block, together with suitable hoisting apparatus near the derrick floor and a 10 suitable pulley block which has a plurality of sheaves around which, and around some of the sheaves of the crown block, a wire hoisting rope is threaded.

The service required of this hoisting equipment is very severe and any failure thereof is very expensive, since wells are often ruined by dropping the pipe or tools therein. Since the investment in any such well, neglecting prospective profits, may exceed one hundred thousand dollars, it is obvious that any failure of the hoisting equipment, which may easily ruin the well, is a very serious matter.

It is an object of my invention to prolong the life and increase the reliability of such equipment by reducing the wear on the rope and sheaves and by eliminating side strains on the sheaves of the crown block.

30 Further objects and advantages will be made evident herein.

Referring to the drawings which are for illustrative purposes only:

Fig. 1 is a side elevation of my invention applied to an oil well derrick.

Fig. 2 is a similar view on an enlarged scale, the crown block being omitted.

Fig. 3 is a front elevation.

Fig. 4 is a section on a plane represented by the line 4—4 of Fig. 2.

In the form of the invention illustrated, I provide a crown block consisting of sheaves 11 and 12 mounted on suitable shafts which are supported on an I-beam structure 13, this structure being supported on the cross beams 14 of the derrick. A wire line 20 extends upwardly from the derrick floor and engages one of the sheaves 12.

50 The wire line 20, due to the position of the apparatus to which it is attached at the lower end, does not lead to the sheave 12 in the plane of the rope groove of that sheave, but extends upwardly at an angle thereto. It is possible, if this angle is not

too great, to operate with the wire line passing directly to the sheave 12, but in such an event there is considerable wear on the side of the rope groove and there is a side strain on the sheave. As a result the sheave and the rope tend to wear. There is some 55 tendency for the rope to jump off the sheave and the crown block and its supporting structure is subject to a side strain. To prevent this side strain and for the purpose of leading the rope 20 to the sheave 60 12 on the central plane of the sheave I provide roller means 30, this roller means consisting of a cylindrical roller mounted to turn freely on a shaft 31. The shaft 31 is flattened as shown at 32, and rests upon a 65 bracket base 33. This bracket base is provided with a T slot 34. Sliding freely on the bracket base 33 is a bracket 35, this bracket engaging the top of the shaft 31 and being provided with ears 36 extending 70 down on either side of the flattened upper surfaces 37 on either side of the bracket base 33. Bolts 38 pass through the bracket 75 35, the heads 39 of the bolts 38 sliding in the T slot 34. These bolts are provided with nuts 40, by means of which the bracket 35 may be clamped down towards the base 33, rigidly securing the shaft 31 thereon. It will be seen that the brackets 35 can be readily moved along the upper surfaces 37 80 of the bracket base 33 so that the position of the bearing means 30 can be readily adjusted. The bracket base 33 is preferably so placed that the bearing means 30 turns 85 about a horizontal axis which is parallel 90 to the central plane of the sheave 12. Due to the construction shown, the shaft 31 can be adjusted towards or away from the central plane of the sheave.

In practice, the derrick shifts a little in position from time 95 to time so that the sheaves must frequently be adjusted so that they will be in proper position relative to the well and the rotary draw works. The cylindrical roller must, therefore, be adjustable so that it may be disposed in proper relation to the sheaves in 100 the crown block.

In practice it is so adjusted that the rope 20, upon leaving the bearing means 30, is in the central plane of the sheaves 12 so that 105 there is no wear on the rope or the sheave due to any irregularity therebetween and so that there is no side strain on the draw

works due to a side pull. The roller means 30 is preferably made in the form of a cylindrical roller so that the rope 20 can adjust itself along the face of this roller to 5 suit conditions, any movement along this face being in the central plane of the sheave 12 and not exerting any side strain thereon.

I claim as my invention:—

1. In an oil well derrick, the combination 10 of: a supporting structure at the top of the derrick; a sheave mounted to turn about a horizontal sheave axis; means for supporting said sheave on said structure; a rope passing over said sheave; roller means turning 15 about a roller axis situated in a horizontal roller axis plane parallel to, but below, a horizontal plane passing through the sheave axis; a shaft upon which said roller means is supported; a bracket base supported 20 on said structure; brackets slideable on said bracket base and adapted to clamp said shaft to said bracket base; and means for securing said bracket to said bracket base.

2. In an oil well derrick, the combination 25 of: a supporting structure at the top of the derrick; a sheave mounted to turn about a horizontal sheave axis; means for supporting said sheave on said structure; a rope passing over said sheave; roller means turning 30 about a roller axis situated in a horizontal roller axis plane parallel to, but below, a horizontal plane passing through the sheave axis, said horizontal roller axis being parallel to a plane passing through the center 35 of the rope groove of said sheave; a shaft upon which said roller means is supported; a bracket base supported on said structure; brackets slideable on said bracket base and adapted to clamp said shaft to said bracket 40 base; and means for securing said bracket to said bracket base.

3. In an oil well derrick, the combination 45 of: a supporting structure at the top of the derrick; a sheave mounted to turn about a horizontal sheave axis; means for supporting said sheave on said structure; a rope passing over said sheave; a bracket secured 50 to said structure below said sheave; a shaft slidably mounted on said bracket; means for securing said shaft to said bracket; and a cylindrical roller mounted on said shaft so disposed as to guide said rope to said sheave in a plane passing through the center of the rope groove in said sheave.

5. 4. In an oil well derrick, the combination 55 of: a supporting structure at the top of the derrick; a sheave mounted to turn about a horizontal sheave axis; means for supporting said sheave on said structure; a rope 60 passing over said sheave; a bracket secured

to said structure below said sheave; a shaft slidably mounted on said bracket; means for securing said shaft to said bracket; and a cylindrical roller mounted on said shaft and turning about a roller axis situated in a horizontal roller axis plane parallel to, but below, a horizontal plane passing through the sheave axis.

5. In an oil well derrick, the combination 70 of: a supporting structure at the top of the derrick; a sheave mounted to turn about a horizontal sheave axis; means for supporting said sheave on said structure; a rope passing over said sheave; a bracket secured to said structure below said sheave; a shaft 75 slidably mounted on said bracket; a clamp adapted to associate said shaft with said bracket; means for securing said clamp upon said bracket; and a cylindrical roller mounted on said shaft so disposed as to guide said rope to said sheave in a plane passing through the center of the rope groove in said sheave.

6. In an oil well derrick, the combination 80 of: a supporting structure at the top of the derrick; a sheave mounted to turn about a horizontal sheave axis; means for supporting said sheave on said structure; a rope passing over said sheave; a bracket secured to said structure below said sheave; a shaft 85 slidably mounted on said bracket; a clamp adapted to associate said shaft with said bracket; means for securing said clamp upon said bracket in a plurality of positions so that the position of said roller may be adjusted; and a cylindrical roller mounted on said shaft so disposed as to guide said rope to said sheave in a plane passing through the center of the rope groove in said sheave.

7. In an oil well derrick, the combination 90 of: a supporting structure at the top of the derrick; a sheave mounted to turn about a horizontal sheave axis; means for supporting said sheave on said structure; a rope passing over said sheave; a cylindrical roller 95 turning about a roller axis situated in a horizontal roller axis plane parallel to, but below, a horizontal plane passing through the sheave axis; a shaft upon which said cylindrical roller is supported; a bracket base 100 supported on said structure; brackets slideable on said bracket base and adapted to clamp said shaft to said bracket base; and means for securing said bracket to said bracket base.

In testimony whereof, I have hereunto set my hand at Los Angeles, California, this 19th day of March, 1924.

EDWIN W. GOESER.
